United States Patent Office

Des. 223,939
Patented June 20, 1972

223,939

GAME BOARD

Thomas P. Palazzolo, 1151 Lakepointe,
Grosse Pointe Park, Mich. 48230

Filed Apr. 1, 1971, Ser. No. 130,555

Term of patent 14 years

Int. Cl. D21—01

U.S. Cl. D34—5

FIG. 1

FIG. 2

FIG. 3FIG. 4FIG. 1 is a perspective view of the game board looking from the top thereof, embodying my new design;

FIG. 2 is a side elevational view looking in the direction of arrow 2 of FIG. 1;

FIG. 3 is a perspective view of the game board looking from the bottom thereof; and

FIG. 4 is a front elevational view looking in the direction of arrow 4 of FIG. 1.

I claim:

The ornamental design for a game board, substantially as shown.
